R. R. WHITING

GAME

Filed May 4, 1925

Robert R. Whiting
INVENTOR
BY *Newell & Spencer*.
ATTORNEY

UNITED STATES PATENT OFFICE.

ROBERT R. WHITING, OF DARIEN, CONNECTICUT.

GAME.

Application filed May 4, 1925. Serial No. 27,653.

To all whom it may concern:

Be it known that I, ROBERT R. WHITING, a citizen of the United States, residing at Darien, county of Fairfield, in the State of Connecticut, have invented a certain new and useful Improvement in Games, of which the following is a clear, full, and exact description.

This invention relates to new and useful improvements in games, and it aims to provide a game which may be played by two or more players, the number of players participating not being limited.

The invention has for one of its objects to provide a game in which the elements of chance may, when combined with good judgement on the part of a player, result in advantage to such player.

The invention has for a further object, the provision of a game which will approximate in many respects the conditions which prevail both on a yacht race course, and during a race between yachts.

It is a further object of the invention to provide a new and improved game which will have educational features such, for example, as teaching the players the "rules of the road" as they pertain to the sailing of ships; certain navigation markings, such, for example, as buoys, lights, etc., and the reading of the compass.

With the above and other objects in view, reference is had to the accompanying drawing, forming a part of the application and which is a plan view of a game board used in the present embodiment of the invention and showing an arbitrary body of water with yacht race courses laid out thereon.

Referring more specifically to the drawings, the reference character A designates a game board which is made of any suitable relatively stiff material such, for example, as card board. If desired the board A may comprise a plurality of sections hingedly connected together in order that the same may fold into relatively compact form.

In carrying out the invention, one surface is provided, preferably by printing with a picturization of a body of water designated by the reference character B, with suitable shore lines C. The shore lines C may have a plurality of projections designated point 1, point 2, etc.

Following generally the contour of certain portions of the shore line, there are lines D

spaced slightly therefrom, and these lines D are used to designate shoal water in that space between them and the shore line. The picturization also includes islands E and designated island 1, island 2, and island 3, and following generally the contour of the island designated island 1, there is a line F used to designate shoal water off the shore line of said island. Projecting from the island designated island 2 there is a line G employed to designate a sand bar or other form of shoal water.

In addition to the foregoing, the picturization will include buoys of all conventional types, light houses, and any other conventional marking devices commonly employed in marking waterways.

There is also a substantially circular line K in the present picturization which line is employed to designate a body of shoal water, which, however, does not follow any particular shore line as in the heretofore described instances.

It is to be understood that the picturization above described is only arbitrary, and that any arbitrary body of water may be employed or, for that matter, a known charted body of water may be employed, without departing from the spirit of the invention, and that the invention will therefore not be limited to the specific picturization employed in the present embodiment thereof.

Extending across the picturization at spaced intervals there are a plurality of series of stations designated by the reference character H. Associated with each of these stations there is a designating character in the form of a value number J, the purpose of which will be hereinafter described.

It will also be noted that there are certain numbers which are not associated with any station such, for example, as those designated by the reference character M. It will also be noted that certain of the buoys and other markings have numbers associated with them, such as those designated by the reference character N.

In addition to shoal water areas, the picturization in the present form of the invention includes rocks submerged as designated by the reference character O, and rocks awash as designated by the reference character P.

Located preferably at the left of the pic-

turization there is a starting point Q and a finishing point R, from which the game starts and at which it finishes respectively. Adjacent the starting point there is a starting stake S and associated therewith there is a group of numbers U, and it will be noted that these numbers are interposed with respect to the starting point and the first transversely extending series of stations heretofore referred to.

While in the present embodiment of the invention, four chance devices L are shown, it is obvious that one or any other number may be employed, it not being necessary to 15 the successful operation of the invention to employ one of these chance devices for each player as they could all use the same one if they so desired.

Each of these chance devices comprises a base *a* which is provided (preferably by printing) with calibrations setting forth 360 degrees of a circle after the manner of a compass, and said calibrations will, in the preferred form of the invention, include 25 identification characters of 1 to 360.

Mounted above the base *a* of each chance device there is a pointer *b* having one of its ends longer than the other. The longer end of this pointer *b* moves over the calibrations 30 of its respective base *a* and cooperates with said calibrations for a purpose to be herein-after described.

The game is played in the following manner. Before starting the game one of the 35 players spins a chance controlled device in order to determine the direction from which the wind is supposed to blow during the playing of the game. This is done for the reason that the "rules of the road" are to be observed by the players in moving their pieces during the playing operations.

The game pieces, designated by the reference character T, are preferably in the form of miniature boats or ships and may, if desired, be of the various types such as sloops, schooners, barks, etc.

The direction of the wind having been determined as above described, each player selects his piece and the game is ready to 50 proceed. In order to determine which of the several players starts first, the chance device is again spun, this time by each of the players, the player registering the lowest number being the first to play, and so 55 on throughout the number of players participating, the player registering the largest number being the last to take his turn.

After the rotation of play of the several 60 participants has been determined, the first player now spins a chance device in the effort to get away from the starting point, and in yacht racing parlance, "round the starting stake".

The movement of a piece by the player is 65 determined as follows. It will be noted

that the numbers associated with the starting stake are 19, 13, 15. If in spinning his chance device the player registers a number having therein one of the digits of either of these three numbers, he would be entitled to move his piece; if the number registered did not include any of the digits of either of these numbers the player could not move his piece and the turn is lost to him. An example of the foregoing will now be given. Assume that the number registered by the player in his turn were 219. The player would then be entitled to move his piece to any one of the three numbers 13, 15, or 19 due to the presence of the number 1 in all four of the numbers; i. e., the reading 219 and the numbers 13, 15, and 19.

When the player chooses the number to which he will move, the following is carried out in order that a final score may be reached. Taking the above as an example, it will be noted that the 9 in 219 corresponds to the 9 in 19 of the figures U. If then the player selects 19 to which to move the 9 in each is cancelled. This leaves 1 uncancelled. The player now takes this 1 to his credit to aid in determining the final score which will be discussed more in detail hereinafter. If, however, the registered number were 202 for example, there would be no digit to cancel a digit of any of the numbers U and the player would therefore be unable to move in that particular turn of play.

The game is continued in the above described manner, the pieces being moved from number to number with the digits uncancelled being placed to the credit of the player, it being understood, however, that the player moves his piece but one station, or to a station in the next series in advance of the series in which a station is occupied by him.

Assuming now that a player's piece occupied the station 53 in the channel between the "shoal 1" and the "shoal 2," and in spinning, the chance device would register the number 17. This would entitle him to move either to the station 7 at the entrance of the channel between point 3 and shoal 2, or the number 7 in the shoal water marked by the line K. Assume now that the player chooses the number 7 in the shoal water. In so doing he also accepts the chance of a penalty, as follows. If now in his next two spins of the chance device, he is unable to register a number having a digit which corresponds to a digit of one of the numbers in the next series, or in other words—he is unable to move his piece, he is to be considered "hard aground," and must drop out of the race.

It is to be understood that the true course of the race is from the starting stake S around shoal water K, island 1 between it

and the mainland, between island 2 and the mainland, and around island 3 passing between it and the mainland, and thence to the finish.

- 6 By taking the shorter course a player can finish in fewer moves than by following the true course, but in so doing he accepts chances which may cause him to lose the race or even to withdraw therefrom.
- 10 In addition to the penalty above mentioned, other penalties are imposed. For example, assuming that a player choose to move his piece to No. 14 adjacent the shoal water K which number 14 is connected to buoy N, he would be considered as having fowled the buoy and would be penalized therefor as follows. In addition to taking the uncancelled digits of the number on the picturization, he must also take to his score the uncancelled digits of the number registered upon the chance device. The foregoing penalty also applies to a player who moves his piece to a number in shoal water even though he is able to move away therefrom by a spinning of the chance device, or if in moving from a position in clear water to another position in clear water, his course intercepts any of the danger zones, as determined by a straight line drawn from the occupied position to the new position taken.

30 As each of the players finishes the race, the uncancelled digits are added and the sum total thereof is divided by 60 in order to reduce the number to hours and minutes in order to determine in an arbitrary manner the time consumed in each player covering the course with his piece.

35 For the purpose of encouraging the several players to take the chances attendant moving through the danger zone, a bonus of ten per centum of the total of the uncancelled digits is deducted from the total of such numbers for the player who is first to reach the finish, and thus reduce his score.

40 From the foregoing it is apparent that the present invention provides a game in which the several players may move their pieces over a predetermined course without penalty, or over any of a plurality of optional courses and accepting chances of penalties, the optional courses being the shortest way over the area covered.

45 What is claimed as new is:

1. In a game, a game board having a predetermined complete course of travel, a relatively shorter complete optional course of

travel, and hazards associated only with said relatively shorter complete optional course of travel.

2. In a game, a game board having a predetermined complete course of travel, and a plurality of relatively shorter complete optional courses of travel, hazards associated only with said relatively shorter complete optional courses of travel, a plurality of game pieces for movement over either of said courses of travel at the option of a person playing the game, and a chance device for determining the movement of said game pieces over their respective courses. 60

3. A game comprising a board, a plurality of areas representing deep water, a plurality of areas representing shoal waters, a plurality of stations associated with each of said areas, a value designation associated with each of said stations, a predetermined course laid through the deep water areas, and marked by said value designations, optional courses laid through the shoal water areas, value designations associated with said optional courses, means for chance selections of numbers corresponding to certain of said value designations in both the deep and shoal water areas, and game pieces movable at the player's option in accordance with the 75 chance selections over the predetermined deep water course or an optional shoal water course. 80

4. In a game, a game board, a deep water area represented on said board, a plurality of shoal water areas represented on said board and arranged adjacent the deep water area representation, a plurality of stations in both the deep water area and the shoal water areas, said stations providing a predetermined course through the deep water area and optional courses through the shoal water areas, a value designation character in the form of units 0-9 associated with each of said stations, there being a greater variety 90 of said characters associated with the stations in the deep water areas as compared with those in the shoal water areas, a plurality of pieces movable over said areas from station to station, and chance controlled 95 means for determining the movement of said pieces in any of said areas at the option of the player. 100

105 Signed at Hempstead this 18th day of April, 1925.

ROBERT R. WHITING.
